CLAIM

The ornamental design for a support frame assembly, as shown and described.

DESCRIPTION

FIG. 1 is a front view of a support frame assembly;
FIG. 2 is a rear view thereof;
FIG. 3 is an upper left perspective view thereof;
FIG. 4 is a lower left perspective view thereof;
FIG. 5 is an upper right perspective view thereof;
FIG. 6 is a lower right perspective view thereof;
FIG. 7 is a left side elevation view thereof;
FIG. 8 is a right side elevation view thereof;
FIG. 9 is a bottom plan view thereof; and,
FIG. 10 is a top plan view thereof.

1 Claim, 10 Drawing Sheets(56)
